(57) **CLAIM**

The ornamental design for a door mounted exercise apparatus, as shown and described.

DESCRIPTION

FIG. 1 is a top perspective view of a door mounted exercise apparatus, with a hook and loop fastener securing the apparatus around the door showing my new design in its environment of use;

FIG. 2 is a left side elevation view, the right side elevation view being a mirror image thereof;

FIG. 3 is a rear elevation view thereof;

FIG. 4 is a front elevation view thereof;

FIG. 5 is an alternate front elevation view thereof;

FIG. 6 is a top plan view thereof;

FIG. 7 is a bottom view thereof; and,

FIG. 8 is a partially enlarged front perspective view thereof, taken from FIG. 1.

The portion of the strap that attaches to the door shown in broken lines is for the purpose of illustrating portions of the door mounted exercise apparatus, which forms no part of the claimed design.

The door and figure shown in broken lines in the drawings are for the purpose of illustrating environmental structure, which form no part of the claimed design.
